GEM SETTING

Julius C. Link, Brooklyn, N. Y.

Application August 9, 1939, Serial No. 289,101

5 Claims. (Cl. 63—27)

This invention relates to jewelry; and more particularly to improvements in settings or mountings for holding ornamental gems and precious stones in articles of jewelry.

5 Heretofore, diamond chips, often called "rose" diamonds, have been provided with a backing of reflecting metal foil or the like in order to impart lustre and brilliancy to the same. Such settings have been found objectionable in that they do not fully reflect the light. When the setting loses its brilliancy due to the reflecting metal foil becoming tarnished by dust, dirt or the like, it becomes difficult to clean the same to restore its brilliancy and the effect of the metal foil is thus destroyed. For this reason, the diamond chips were considered of little value, and the extensive use of the chips has been restricted.

The primary object of this invention is to 20 provide a mounting for "rose" diamonds or diamond chips, in which the use of reflecting metal foil or the like can be dispensed with, and in which said mounting is provided with reflecting surfaces which can be readily and easily 25 cleaned when desired.

A further object of the invention is to provide a mounting with a reflecting surface which greatly extends the field of use of such diamonds or diamond chips, particularly in the provision 30 of high-cost jewelry, as well as in the provision of low-cost-jewelry.

35 A further object of the invention is the provision of a setting for diamonds or diamond chips in which the reflecting surfaces are in the form of a pyramid with the diamond preferably resting upon the apex of the pyramid, thus providing a plurality of reflecting surfaces for directing the light on the underside of the stone, thereby increasing the brilliancy and lustre 40 thereof.

45 These and other advantageous objects, which will later appear, are accomplished by the simple and practical construction and arrangement of parts hereinafter described and exhibited in the accompanying drawing, forming part hereof, and in which:

50 Fig. 1 is a side elevational view of a finger ring having settings embodying my invention, the particular ring shown being adapted for use as a wedding ring,

Fig. 2 is a plan view of several settings shown in Fig. 1,

55 Fig. 3 is a sectional view taken on line 3—3 of Fig. 2,

Fig. 4 is a side elevational view of a finger ring having settings embodying my invention,

Fig. 5 is a top plan view of the setting,

Fig. 6 is a bottom plan view of the setting,

Fig. 7 is a sectional view taken on line 7—7 of Fig. 5, and

Fig. 8 is a side elevational view of the setting.

Referring to the drawing, there is shown a setting comprising a base 10 from which projects a four-sided pyramid 11, providing four reflecting 10 surfaces. Extending upwardly from the base 10 are four prongs 12 which have the upper surfaces thereof provided with notches 13 to facilitate the upsetting of portions of the prongs over the girdle of a diamond or other stone 14 to hold it 15 rigidly in the setting.

A "rose" diamond is relatively thin and has a flat under surface, which, when mounted in the above described setting, preferably rests upon the apex of the pyramid 11, the prongs 12 being 20 upset over the upper surface of the diamond.

It will be seen that the sides of the pyramid effectively reflect light upwardly through the undersurface of the diamond and increases the brilliancy thereof. Also, should the setting lose 25 some of its brilliancy and lustre due to its being subjected to dirt, dust or the like, it can be readily cleaned, as the parts subjected to the dirt and dust are conveniently accessible.

30 By means of the setting herein described, the field of use of "rose" diamonds, that is, diamond chips, may be extended; and it is now possible to produce articles of jewelry with "rose" diamonds to attain an effect similar to that attained by using a properly cut diamond. The operation of 35 mounting a stone in the setting obviously is simple, and at the same time the stone is rigidly and securely mounted in the setting.

40 The foregoing disclosure is to be regarded as descriptive and illustrative only, and not as restrictive or limitative of the invention of which obviously, embodiments may be constructed, including many modifications, without departing 45 from the spirit and scope of the invention herein set forth and denoted in the appended claims.

Having thus described my invention, what I 50 claim as new and desire to secure by Letters Patent, is:

1. In a gem setting, a base having a pyramid projecting upwardly therefrom, the apex of said pyramid being in close proximity to a stone, and prongs projecting upwardly from the base, said prongs being adapted to receive a stone.

2. In a gem setting, a base having a four-sided pyramid projecting upwardly therefrom, the apex 55

- of said pyramid being adapted to engage and support a stone, and prongs projecting upwardly from the base to engage a stone resting upon the apex of the pyramid.
5. 3. In a gem setting, a base having a plurality of flat inclined upper reflecting surfaces and provided at the center thereof with means to receive the flat surface of a stone, and prongs projecting upwardly from the base to engage a stone.
- 10 4. In a gem setting, a base having a four-sided pyramid projecting upwardly therefrom, and prongs projecting upwardly from the four corners

of the base of the pyramid, said prongs being adapted to engage a stone resting upon the apex of the pyramid.

5. In a gem setting, a base having projecting upwardly therefrom a pyramid with a plurality of inclined reflecting surfaces, and a plurality of prongs projecting upwardly from the corners of the base of the pyramid, said prongs being adapted to engage a stone resting upon the apex of the pyramid.

JULIUS C. LINK.
